UNITED STATES PATENT OFFICE.

LOUIS BOURQUIN, OF NEW ORLEANS, LOUISIANA.

MACARONI DIE-PLATE.

SPECIFICATION forming part of Letters Patent No. 762,128, dated June 7, 1904.

Application filed September 26, 1903. Serial No. 174,788. (No model.)

To all whom it may concern:

Be it known that I, LOUIS BOURQUIN, a citizen of the United States, residing at New Orleans, in the parish of Orleans and State of 5 Louisiana, have invented a new and useful Macaroni Die-Plate, of which the following is a specification.

My invention relates to the die-plates used in connection with machines for manufacturing macaroni and similar products, the said plates being arranged at the lower end of the cylinder holding the dough, which is forced through the die-plate by means of a suitable plunger. Considerable difficulty is experienced in cleaning these plates; and the object of 15 my invention is to provide a die-plate formed in sections and readily taken apart and to provide pins fitting in the opening in said plate, the said pins being readily removable when 20 the two sections have been taken apart, thereby enabling all parts of the die to be easily cleaned.

A further object of my invention is to so shape the pins that they will automatically center when dropped into position, so that no special care or skill is required to be exercised in putting the die-plate together after cleaning.

My invention consists in the novel features of construction and combination of parts hereinafter described, particularly pointed out in the claims, and shown in the accompanying drawings, in which—

Figure 1 is a side elevation of a cylinder of a macaroni-machine, partly broken away at 35 the lower end and shown in section and showing in section my die-plate in position, the pins being shown in elevation. Fig. 2 is a plan view of my die-plate. Fig. 3 is an inverted plan view of the same plate. Fig. 4 is 40 a vertical section through a portion of the plate. Fig. 5 is a perspective view of one of the pins.

In the drawings, A represents the usual dough-cylinder open at each end and resting 45 on a platform A', having a circular opening A², registering with the lower end of the cylinder, but of slightly smaller diameter than the interior diameter of the cylinder at its lower end. The cylinder is provided with the 50 side standards B, and above the cylinder and

bearing on the standards B are the guide-standards B', between which slides the usual plunger B². The bracket B³ (shown as broken away in Fig. 1) supports a portion of the plunger-actuating mechanism. 55

The parts above mentioned are shown and described to give a clearer understanding of the manner in which my die-plate is used and are found substantially as shown in all machines used for the purpose for which this die 60 is intended.

My die consists of a circular plate C, having a diameter adapting it to fit snugly in the lower portion of the cylinder A and to rest on the marginal portions of the platform A', encircling the aperture or opening A², which opening is covered by the die-plate C. This plate has formed in it a plurality of tapering vertical apertures, the walls of said apertures converging inwardly and downwardly, as is 70 clearly shown at C in Fig. 4, the lower ends of the apertures being shown at C' in Fig. 3. A circular plate C² is adapted to rest on the plate C, and the plate C² has a plurality of openings C³ formed therein and equal in number to the apertures C' of the plate C and arranged so as to aline with said apertures. 75 The upper portions of the openings C³ have beveled or outwardly-flaring walls, as shown at C⁴, but at their lower ends the openings C³ 80 are slightly smaller in diameter than the apertures C', the cylindrical pins D having radiating webs D' adjacent their upper ends, the side edges of the webs being notched, as at D². These webs fit snugly in the upper portion of 85 the apertures C', their upper ends lying flush with the top of the plate C, and the lower ends of the pins, which are centered by the webs in the apertures, project below the bottom of the plate. 90

Sockets, preferably three in number, are formed in the top of the plate C in its marginal portion, and pins E, carried by the plate C², fit in these sockets. A threaded socket is formed in the center of the plate C and is engaged by a screw E', passing through the center of the plate C². The pins E prevent the plate C² from rotating on the plate C and throwing the openings C³ out of alinement with the openings C'. 95 100

It will be obvious that when the plate C³ is in position the pins D can have no vertical movement in the apertures of the plate C; but when the die has been removed from the cylinder for cleaning it is only necessary to take out the screw E' and lift up the top plate. As previously stated, the lower ends of the pins D project below the plate C, and after the top plate has been removed by setting the plate C on a table or other smooth surface and bearing down on same the webs of the pins are forced up out of the apertures above the top of the plate C, thus loosening them from the dough remaining in the apertures and which would tend to hold them in their seats, especially if dry, and then by turning the plate bottom upward all the pins will fall out, and all parts of the die can be washed and cleaned. In putting the die together again it is immaterial which aperture any special pin is placed in, and as each pin is dropped into an aperture the web will center it without calling for any special care or skill on the part of the person doing the work, and in the same way the pins E of the top plate will when fitted into their sockets center the said plate, so that the openings C³ will align properly with the apertures C.

Having thus fully described my invention, what I claim as new, and desire to secure by Letters Patent, is—

1. A die of the kind described comprising upper and lower plates having aligning openings; webbed pins held centrally in the openings of the lower plate and held in place by the upper plate, and means for detachably fastening the two plates together.

2. A die of the kind described comprising a lower plate having downwardly-tapering openings formed therein, pins having radiating webs formed on their upper portions, and adapted to fit in said openings, an upper plate having openings formed therein adapted to align with the openings of the lower plate, the said openings being at their lower ends of less diameter than the upper portions of the openings of the lower plate, and means for

fastening said upper plate detachably to the lower plate.

3. A die of the kind described comprising a plate having tapering openings formed therein, pins having a webbed portion adjacent their upper ends, said web portions fitting in the upper portions of the openings and the lower ends of the pins extending below the plate, a top plate adapted to fit over the first-mentioned plate and having openings therein adapted to align with the openings of the first-mentioned plate and of a less diameter than the upper ends of said openings, and means for fixedly and removably securing said top plate to the first-mentioned plate.

4. A die of the kind described comprising an upper plate having a plurality of openings beveled in their upper portions, depending pins carried by the marginal portions of said plate, the said plate having a central perforation, a lower plate having downwardly-tapering openings of a greater diameter at the top than the bottom diameter of the openings in the upper plate, the lower plate having sockets in its marginal portion adapted to receive the pins carried by the upper plate and a threaded central socket adapted to register with the central perforation of the upper plate, the openings of the upper plate aligning with those of the lower plate when the said pins are in engagement with the sockets, pins having an upper web portion adapted to fit in the upper portion of the openings of the lower plate and to lie flush with the top of the lower plate, the lower ends of said pins extending below the bottom of the lower plate and the said pins being spaced by the webs from the walls of the openings in which they are seated, and a screw adapted to pass through the central perforation of the upper plate and engage the threaded socket of the lower plate.

LOUIS BOURQUIN.
